UNITED STATES PATENT OFFICE.

GEORGE M. JOHNSON, OF JEANNETTE, PENNSYLVANIA.

MINE CAGE.

Application filed February 24, 1921. Serial No. 447,594.

To all whom it may concern:

Be it known that I, GEORGE M. JOHNSON, a citizen of the United States, residing at Jeannette, in the county of Westmoreland and State of Pennsylvania, have invented 5 certain new and useful Improvements in Mine Cages, of which the following is a specification.

This invention relates to mine cages, and 10 has for its object to provide, in a manner as hereinafter set forth, means connected or secured with the bottom or deck of the cage to prevent the buckling, sagging or bending of said bottom or deck when the cage is 15 shifted to and from normal position and when being tilted, and to further provide the bottom or deck of the cage with means to provide a clearance during the movement of the cage to prevent injury to the operating rod of a car block releasing mechanism on the bottom or deck and also to prevent injuring to the actuating lever, arranged at a landing, for said operating rod.

Further objects of the invention are to 25 provide a mine cage which is simple in its construction and arrangement, strong, durable, having its bottom or deck re-inforced to prevent buckling or sagging thereof, readily set up and comparatively inexpensive.

With the foregoing and other objects in 30 view the invention consists of the novel construction, combination and arrangement of parts, as hereinafter more specifically described and illustrated in the accompanying drawings wherein is shown an embodiment of the invention, but it is to be understood that changes, variations and modifications can be resorted to which come within the 35 scope of the claims hereunto appended.

In the drawings wherein like reference 40 characters denote corresponding parts throughout the several views:

Figure 1 is a side elevation of a mine cage in accordance with this invention,

Figure 2, is a top plan of the bottom or deck broken away,

Figure 3 is a front elevation.

Figure 4, is a fragmentary view illustrating the brace member associated with the 50 clearance in the front edge of the deck.

Referring to the drawings in detail the bottom or deck 1 is constructed of structural steel, beams and plates, and is cutaway at its front, as at 2, forming a passage to provide a rectangular clearance, so that during

the ascent or descent of the cage the operating lever for the operating rod of the block shifting mechanism on the cage, if such lever is projected can clear through said passage, or that the operating rod, 55 which has a hinged section, can be swung inwardly if it meets with an obstruction. A brace member 3, which is arranged below the top of the deck, registers with the walls of the passage forming continuation of the clearance. Track rails 4 are secured upon the deck 1, and secured to the deck 1 and projecting upwardly therefrom are the sides of the cage, and which are termed upper side plates and are indicated at 5.

To prevent the buckling or sagging of the deck 1, the cage includes a pair of lower side plates 6, which are triangular and depend from the deck 1. The plates 6 are of less length than the length of the deck 1, and are formed with inwardly extending flanges as at 7. The lower portion of the plates 6 are cutaway to provide clearance for the bearings 8 for the shaft 9. The plates 6 are arranged inwardly with respect to the side bars 10 of the cage, these latter supporting the bearings 8 and extend above and below the deck 1. The lower ends of the bars 10 are connected together by a cross member 11. The top of the plates 6 abut 70 against the lower face of the deck 1.

Positioned against the sides of the deck 1, as well as being secured to each side of the deck, is a coupling plate 12, which extends slightly above the deck. The plates 12 are 80 of a length equal to the length of the deck, and each of the plates 12, has a depending portion 13, of less length than the length of its respective plate and which overlaps and is secured to a lower side plate 6, by the securing devices 14, under such conditions the lower side plates are coupled with the deck 1, and in connection with the coupling plates prevent the deck 1, from sagging or buckling, and further act as a support for the deck. The lower side plates are also secured to the bearings 8 and as such plates are flanged they are very rigid.

What I claim is:

1. A mine cage comprising a deck having 105 its front edge between the center of the deck and one side edge thereof provided with a vertical passage constituting a clearance, and a brace member arranged below the top of the deck and registering with the walls of 110

the passage forming a continuation of the clearance.

2. A mine cage comprising a deck, a pair of side plates depending from the bottom of the deck and flush with the sides of the latter, said plates provided with inwardly extending flanges below the deck, and a pair of

coupling plates secured to and depending from the sides of the deck and overlapping and secured to the upper portion of the side plates.

In testimony whereof I affix my signature.

GEORGE M. JOHNSON.
